UNITED STATES PATENT OFFICE.

ROBERT GEORGE MARSH, OF DETROIT, MICHIGAN.

ICE-BOX CONSTRUCTION.

Application filed September 10, 1923. Serial No. 661,859.

When ice is used as a refrigeratory agent in boxes, ice cream cabinets and soda fountain compartments there is ordinarily a condensate which should be removed to prevent 5 deterioration of the material forming the walls of the box, cabinet or compartment.

My invention aims to provide an ice box construction which affords a chamber in which the condensate may accumulate and 10 be readily removed as it accumulates.

My invention also aims to provide a cabinet construction for soda water fountains which will provide an ice compartment for ice cream containers or cans, and another 15 compartment to receive cold water from the ice compartment, so that the cold water may be used for cooling bottles or other containers placed therein. The water receiving compartment of the cabinet is constructed 20 so that the supply of water thereto may be controlled, also the outlet of water, and all of this is accomplished without changing any standard design of cabinet and without materially increasing the cost of production.

25 My invention will be hereinafter described and reference will now be had to the drawing, wherein

Figure 1 is a perspective view of a soda water fountain having a cabinet or ice box 30 in accordance with my invention;

Fig. 2 is a longitudinal sectional view of the cabinet or ice box; and

Fig. 3 is an enlarged vertical sectional view of a detachable overflow pipe or connection for the drain compartment of the 35 cabinet or ice box.

In the drawing, the reference numeral 1 denotes an outer casing having legs or supports 2 resting on a floor 3, and said casing 40 is provided with a transverse partition 4 dividing said casing into two compartments, one larger than the other. The inner walls of the casing compartments are each provided with a metallic lining 5 and in each 45 compartment is a metallic inner casing 6. Between the inner casing 6 and the metallic linings 5 are linings of water proof and insulation material 7, preferably in the form of blocks or sections of cork, asbestos or any 50 material possessing water proof and insulating characteristics which will more or less isolate the inner casings 6 from the outer casing.

One of the inner casings is adapted to 55 hold a refrigerant, as ice 8 in which may be

placed an ice-cream container or other receptacle 9.

The other inner casing is adapted to hold cold water 10 in which may be placed bottles 11 or other receptacles, and on account of 60 such cooling agents causing condensation, waterproof spacing members 12 have been placed between the bottom of the outer casing and the linings of insulation material at the bottoms of the inner casings. The 65 spacing members 12 may be in the form of perforated corrugated galvanized sheet metal with the corrugations affording spaces for the accumulation of condensate adapted to be removed through drain pipes 70 13 extending through the bottom of the outer casing 1 and the floor 3. The corrugated metal may be in small loosely joined pieces which will readily permit any condensate to pass therebetween and reach the inner face 75 of the lining 5 and flow off through the pipe 13. These drain pipes or connections may have traps 14 preventing air from entering the condensation chambers in the outer casing and with said chambers sealed, 80 the air therein will serve for insulating purposes.

Extending from the ice holding inner casing into the water holding inner casing is a 85 drain pipe or connection 15, which extends through the partition 4 and has a conventional form of valve 16 within the water holding casing. The admission of ice water to the water holding casing may be controlled by the valve 16, and in order that 90 water may be drained from the water holding casing or a predetermined level of water maintained therein, said casing is provided with a drain pipe or connection 17 and an overflow pipe or connection 18. The drain 95 pipe 17 is provided with a valve 19 to control the drain of water through said pipe and said pipe has a funnel shaped mouth or seat 20 at the bottom of the water holding casing to receive the conical end 21 of the 100 overflow pipe or connection 18. With this pipe or connection in place, as shown in Fig. 2, and the valve 19 opened, the level of water will be maintained at the upper end of said pipe or connection. Should it be desired to 105 remove the water the overflow pipe 18 can be removed.

In Fig. 1 I have shown the ice box construction embodied in a small soda water fountain having faucets 22, flavor contain- 110

ers 23, and a drain board 24. This drain board may be located at the upper end of the water holding inner casing at one end of the fountain, while the ice holding compartment may occupy the greater part of the opposite end of the fountain. The last mentioned compartment or casing may be normally closed by a lid 25 contributing towards the support of the ice cream container or receptacle 9 surrounded by the ice 8.

In such refrigeratory boxes, showing condensate, which I have examined, the insulation material is very often soaked and loses, to a great extent, its insulating qualities, whereas boxes in accordance with my invention show that the insulation is perfectly dry and there is no deterioration due to dampness or the accumulation of any con-

densate. This provides a better refrigerator or ice box and does not materially increase the cost of manufacture.

One embodiment of my invention has been illustrated, but it is to be understood that the construction is susceptible to such changes as are permissible by the appended claim.

What I claim is:—

An ice cream cabinet comprising an outer casing, an inner casing, a lining of insulation material about said inner casing, spacing means between the lining of insulation material and the bottom of said outer casing, and a drain connection for each casing.

In testimony whereof I affix my signature.

ROBERT GEORGE MARSH.
